PROCESSING OF HYDROCARBONS

Rhett G. Harris, Charleston, S. C., and Raymond J. Strawn, Long Beach, Calif., assignors to Texaco Development Corporation, New York, N. Y., a corporation of Delaware

No Drawing. Application August 17, 1950,
Serial No. 180,092

8 Claims. (Cl. 195—1)

This invention relates to the production of biosynthetics from hydrocarbons and more particularly to the production of fat-like saponifiable materials, organic acids and antibiotic substances from hydrocarbons by the action of microorganisms such as molds, yeasts and the like.

It has been known for some time that such microorganisms have the ability to attack or metabolize some material such as carbohydrates. Since carbohydrates are relatively expensive raw materials and in most cases, of greater value than the products produced therefrom, other raw materials have been sought. A considerable amount of work has been done with hydrocarbons but to date it has not been generally successful and has not been on a practical basis, apparently because of the failure to appreciate certain factors as hereinafter described. Probably the most discouraging aspect of the hydrocarbon work done heretofore is the fact that the principal products have been carbon dioxide and water. Apparently, this has been due to a studied adherence to established methods of procedure and a failure to appreciate the possible effects of radical departures therefrom.

Accordingly, it is an object of this invention to provide novel processes wherein hydrocarbons can be effectively utilized in biosynthesis including the production of fat-like saponifiable materials, organic acids and antibiotic substances.

Another object of this invention is the provision of a series of novel products from hydrocarbons including fat-like saponifiable materials, organic acids and antibiotic substances.

Still another object of the invention is the provision of novel methods for recovering such synthesized products.

Other objects and advantages of the invention will appear from the following description taken in connection with the attached claims.

In brief, it has been discovered that under certain conditions, microorganisms such as molds, yeasts and the like can be caused to grow quite rapidly upon relatively inexpensive substrates such as hydrocarbons with the production of relatively large yields of desirable products including fat-like saponifiable materials, antibiotic substances and organic acids. Such conditions include such factors as the selection and maintenance of a proper pH range and temperature range, and the selection of proper nutrient salts. In some cases, the selection of predetermined concentrations of both salts and substrates is desirable.

Broadly stated, the practice of the invention involves the use of a nutrient salt solution such as a solution of the mineral salts type with a pH in a selected range and the use of a hydrocarbon, the inoculation of the mixture with a selected microorganism or microorganisms, the maintenance of the mixture within predetermined temperature and pH ranges a time sufficient to effect the desired biosynthesis, and the recovery of the desired products.

Any type of hydrocarbon can be utilized in the process. Good results have been obtained with complex hydrocarbons such as crude oil, kerosine, paraffin wax, naphtha, gasoline, gas oil, lubricating oils and bottom sediments from oil tanks. Of the above, even better results have been obtained with certain selected cuts. For instance, a kerosine water white oil, sold by The Texas Company under the trade name "Crystalite" and having a B. P.

2

range of 178° C.—261° C. was fractionated into the following cuts:

5	Cut	B. P., ° C.	Refraction Index	Specific Gravity
A	to 205	1.4388	0.8022	
B	205-215	1.4432	0.8118	
C	215-225	1.4454	0.8155	
D	225+	1.4500	0.8217	
10 Control or Charge	178-261	1.441	0.8118	

Of the above cuts of kerosine, Cut D was found to give the best yield and product as expressed in grams of mold mycelia. Cut D gave a yield of over twice as much as Cut A, about 50% more than Cut B and about 33% more than Cut C.

Commercial stove oil, having a B. P. range of 167° C. to 277° C. was similarly fractionated by A. S. T. M. distillation methods into the following four cuts:

25	Cut	B. P., ° C.	Refraction Index	Specific Gravity
F	to 221	1.4541	0.8279	
G	221-235	1.4583	0.8351	
H	235-252	1.4631	0.8415	
I	252+	1.4681	0.8506	
30 Control or Charge	167-277	1.4590	0.8304	

Of the above, Cut I gave a yield of about three times the yield of Cut F measured in mold mycelia, of about twice the yield of Cut G and about 1½ times the yield of Cut H.

35 Relatively simple hydrocarbons such as isopentane, n-pentane, 2,2-dimethylbutane, 2,2,4-trimethylheptane, n-heptane, isoheptanes, isoheptenes, iso-octanes, iso-octenes, 2,3-dimethylpentane, cyclopentane, butylbenzene, 2,2,5-trimethylhexane, 2,3-dimethylpentane, 2-pentene, 40 methyl-cyclopentane, and 1-pentene can also be used as well as hexane.

Microorganisms suitable for use include molds, yeasts and the like. Typical examples are molds of the genus Penicillium such as *P. roqueforti*, *P. glaucum*, *P. chrysogenum*, *P. patulum*, and *notatum*, molds of the genus Aspergillus such as *A. fumigatus* (strain TDC #946), *A. carbonarius*, *A. niger*, *A. flavus* and *A. terreus*. Typical yeasts include *Monilia murmamica*, *Monilia sitophila* and *Saccharomyces*.

50 The majority of the above were secured and are available from the American Type Culture Collection. One such mold that is suitable for use was unidentified except for the number 9577.

One of the best microorganisms for use in the process 55 of this invention has been found to be *Aspergillus fumigatus* strain TDC No. 946) which has been identified as follows:

Source of isolation.—A mixed sample composed of soils taken from areas in which oils were undergoing decomposition and water taken from sumps, tank bottoms, and waters which had been in contact with refinery wastes; decomposing asphalt, wax and used motor oil were included in the sample.

Date of isolation.—October 1, 1947.

Location of isolation.—Signal Hill Laboratory, The Texas Company, Long Beach, California

Media used for isolation.—A hydrocarbon-mineral salts medium composed of 5% Arabian crude oil (topped) and the following medium at pH 4.5.

70 Compound:	NaNO ₃	grams/liter	2.0
	KH ₂ PO ₄	do	1.0
	MgSO ₄ ·7H ₂ O	do	0.5
	KCl	do	0.05
	FeSO ₄ ·7H ₂ O	do	0.01
	Sea water	milliliters	10.0
	Distilled water	do	990.0

The above is generally designated Turfitt's Yeast and Mold Medium.

Conditions of isolation.—Aerobic, at 40° C.

Microscopic examination and a comparison of the essential morphological features with those of molds described in the literature indicate that the mold belongs to the *fumigatus* group of the *Aspergilli*, the type species of which is *Aspergillus fumigatus*. A complete description thereof can be found in "A Manual of the *Aspergilli*" by Charles Thom, The William and Wilkins Company, Chapter X, pp. 148-151.

The character of the nutrient media or mineral salts solution will vary to some extent in accordance with the type of microorganism used and the type of hydrocarbon. Generally, it should contain N, P, K, S, Fe, Mg, the general composition being well known in the art. A typical medium is as follows:

Compound:

(NH ₄) ₂ SO ₄	grams/liter	2.0
K ₂ HPO ₄	do	2.0
NaH ₂ PO ₄	do	1.0
MgSO ₄	do	0.25
MnCl ₂	do	0.01
CaCl ₂	do	0.01
FeSO ₄	do	0.01
KI	do	0.00001
CuSO ₄	do	0.00001
Distilled water	milliliters	1000

In some cases, the medium may be fortified or enriched with accessory growth factors such as water extract of yeast as *Saccharomyces cerevisiae*.

It is to be understood that the character of the medium may also be varied dependent upon the type of product that it is desired to produce in the most abundance.

As regards the mechanical or contact aspect, the process may be practiced in a number of different ways. In its simplest form, the growth may be accomplished in a static phase on the surface of the liquid mixture.

In the alternative, it may be practiced as a deep culture process by mechanical agitation such as stirring or shaking in the case of liquids. In the case of solid hydrocarbons, contact may be established and maintained by the method described in the copending application of Rhett G. Harris, S. N. 12,896 filed March 3, 1948 and entitled Processes Involving the Action of Micro-organisms or Their Enzymes on Organic or Inorganic Substances wherein the hydrocarbon is adsorbed on a finely divided and relatively inert adsorbent material such as a clay. Where the hydrocarbon is in the gaseous phase, a system may be set up wherein the gas is recycled through the inoculated medium.

The pH with molds may vary from 1 to 9. With yeasts, the pH may vary from 4 to 9. Its selection is governed by the particular microorganisms, the particular hydrocarbon and the end products desired.

The same is true of temperature, the range being from 20 to 45° C. The actual time of incubation, usually from 7 to 12 days, is determined by the rate of growth of the microorganisms and the rate of production of the desired by-products. This is governed by the ability of the enzymes produced by the microorganisms to effect production of the desired products.

As typical examples of the methods of the present invention, attention is called to the following.

Example I

A. fumigatus (Strain TDC No. 946), previously identified, kerosine cuts of the types previously identified as cuts A, B, C, and D (about two parts by volume) and a nutrient medium (about 30 parts by volume) were combined under incubating conditions at a temperature of 28 to 30° C. for about one week. The nutrient medium in this case was of the following approximate composition:

Compound:

NaH ₂ PO ₄ .2H ₂ O	grams/liter	1.0
K ₂ HPO ₄	do	2.0
MnCl ₂ .4H ₂ O	do	0.01
CaCl ₂ .2H ₂ O	do	0.01
KI	do	0.00001
(NH ₄) ₂ SO ₄	do	2.0
MgSO ₄ .7H ₂ O	do	0.25
FeSO ₄ .7H ₂ O	do	0.01
CuSO ₄ .5H ₂ O	do	0.00001
Sea water	milliliters	10.0
Distilled water	do	990.0

The pH of the above medium was adjusted to about 5.5 because of it being a good pH value for mold growth and a good pH value for inhibiting bacterial contamination.

After incubation for about one week, the growth was harvested by straining and squeezing to remove excess hydrocarbon and medium. The solid material was then dried at 90° C. to 105° C. for about twenty-four hours, extracted with chloroform, and the fat-like saponifiable material taken from the chloroform in a yield of about 11%.

Referring more specifically to the method of extraction, the mycelia were harvested as by straining and squeezing, dried and a crude extract prepared by chloroform extraction. After removal of the solvent, the residue was treated with approximately two-thirds its weight of potassium hydroxide dissolved in alcohol and refluxed to effect saponification. Following saponification, about two-thirds of the solvent alcohol was removed by heating. The residual soap solution was then extracted with petroleum ether to remove the non-saponifiable fraction. Following this step, the aqueous liquor was made strongly acid with a mineral acid and the free organic acids extracted with diethyl ether.

The saponifiable material thus recovered does not consist exclusively of fatty acids of the usual aliphatic character. Some products were found which reacted chemically very nearly the same as the fatty acids but they were not the usual aliphatic fatty acids such as the straight-chain acids containing an even number of carbon atoms such as C₁₀ acid (capric), C₁₂ acid (lauric or dodecanoic), etc., such acids being usually obtained from the naturally occurring fats.

While the time of incubation can be continued for a longer period of time, it has been found that there is only a slight increase in yield on continuing incubation even to the extent of an additional week and incubation beyond that time tends to result in a reduction of yield.

The mixed fatty acids obtained from the above procedure are in the nature of pale yellow solids at room temperature with the characteristic appearance of a fat. A slightly pleasant, fat-like odor is present and the taste is similar to that of candle tallow or similar stearins. The product melts at about 29.5° C. and has a setting point of 17.5° C. The mean molecular weight is 294, and the iodine number, 83.5. Of the common fats or fatty oils, the product most closely resembled the mixed fatty acids from olive oil.

Example II

As an example of an application of the method to the deep-culture technique wherein the reactants are in contact throughout the body of the mixture rather than at an interface, a container was provided with suitable stirring means of a type such that the stirring speed could be controlled. A supply of sterile air was connected so that it could be distributed through a hollow stirring rod and through porous diffusion bulbs attached to the stirring arms. Thirty parts by volume of the nutrient medium above-described in connection with Example I at a pH of about 5.0 was mixed with 2 parts per volume of hydrocarbon such as kerosine and an inoculum of *A. fumigatus* (Strain TDC No. 946) was added. The inoculum was formed as a thick suspension of the organism in nutrient medium constituting about 10% by volume of the total charge. Either air or relatively pure oxygen can be used as the aerating medium. The mixture was stirred constantly for about one week at 28° C. to 30° C. The liquid and the mycelia were separated by a centrifuge and the mycelium treated as described in Example I. Part of the water phase was concentrated and the acids contained therein extracted by ether extraction. Another part of the water phase with the mold removed and not concentrated was sterilized by a bacterial filter (cold sterilization) and tested as later described.

Example III

In this example, a yeast, i. e., *Monilia murmanica* was used as the microorganism in the nutrient medium in the type above described and in combination with kerosine. The deep culture method described in Example II was followed, the resultant mixture being centrifuged to remove the yeast, the water phase treated as in Example II.

In addition to the fatty acids above described, the process has also been found to produce organic acids and an antibiotic substance which is found in the aqueous

phase of the hydrocarbon-mineral salts media after removal of the nutrient and the microorganisms.

In isolating the organic acids as distinguished from the fatty acids, the aqueous phase of the culture was physically separated from the solids and the residual hydrocarbon removed. The aqueous phase was then concentrated under reduced pressure at a temperature of about 60° C. and extracted with diethyl ether. This extract is very sparingly soluble in water, and gives a suspension with an acid reaction. It is a viscous, dark brown liquid with a disagreeable odor. On distillation and continued heating, there is evidence of decomposition without additional distillate, the residue being a dark, very viscous liquid, insoluble in water, giving an acid reaction, soluble in dilute alkali and partially soluble in bicarbonate.

After treatment under esterifying conditions with methanol, the ester was distilled under vacuum and the distillate was saponified. After acidification, the free acids were removed by extraction. The resultant material dissolved in both alkali and bicarbonate and exhibited a neutral equivalent of 209.

Further analysis according to the method of Baker and Bakenbus [Ind. Eng. Chem., Anal. Ed. 9, 135 (1937)] which is a fusion with a potassium carbonate-magnesium mixture indicated the absence of sulfur, nitrogen and halogens.

When the ether extract is saponified, the soap extracted to remove possible non-saponifiables, and after acidification, the acid material recovered by ether extraction, the acid recovery is about 42% of the original sample.

Such acid material is a viscous liquid at room temperature, does not crystallize at 0° C. and has a neutral equivalent of 153. When just neutralized with NaOH to form the sodium soaps and treated with a solution of copper sulfate, a voluminous green-blue precipitate is produced. This copper salt, after isolation and drying will ignite but is insoluble in diethyl ether, petroleum ether, pentane or gasoline.

The iodine number of the acid material is 33. When dissolved to make a 10% solution in acetone, it will not crystallize at temperatures as low as -65° C.

In separating the antibiotic substance, both the microorganisms and the residual hydrocarbon were removed from the liquid by the Sharples super-centrifuge. By a proper choice of califier rings, which choice will vary with the system being handled, it is possible to make a three-way separation into oil, aqueous phase, and solids, the latter containing organisms and precipitated salts. Removal of all finely divided materials and sterilization of the liquor can be accomplished by filtering under suction with a Berkereld or Sela type filter.

In testing for antibiotic action, test organisms were inoculated into nutrient broth and incubated at 30° C. for forty-eight hours. A long incubation period was used because of the slow growing characteristics of some of the organisms that were used and the desire to bring such organisms to their most effective stage. Organisms used included *Pseudomonas aeruginosa*, No. 10147 from the American Type Culture Collection, *Escherichia coli*, No. 9637 from the American Type Culture, *Mycobacterium phlei*, No. 10142 from the American Type Culture Collection, *Mycobacterium smegmatis*, No. 10143 from the American Type Culture Collection and *Bacillus cereus* (mycoides), No. 9634 from the American Type Culture Collection.

An inoculum of 0.1 ml. of the broth culture was added to 20 ml. of sterile, melted nutrient agar at 40° C. to 45° C. in separate test tubes, mixed, and poured into separate Petri plates. After the agar had become solid, circular pieces of sterile filter paper, about 1/2" in diameter, were dipped into the liquor to be tested, allowed to drain free of excess liquid, and placed on the surface of the Petri plate with sterile forceps. The plate with the adsorbed test papers was then inverted and incubated at 30° C. for forty-eight hours. In every case, evidence of antagonistic action was shown by inhibition of the growth of the test organism, i. e., the formation of a clear zone surrounding the test paper adjacent to the test paper.

As a result of the above test, it was found that the sterile filtrates were antagonistic to *Bacillus subtilis*, a Gram-positive spore-forming bacillus, which is a common inhabitant of soil, is non-pathogenic and produces an antibiotic subtilin; *Bacillus cereus*, a Gram-positive,

spore forming bacillus found in soil: *Mycobacterium smegmatis* or the *Smegma bacillus*, an acid-fast, non-spore forming bacillus belonging to the same genus as a tubercle bacillus (*Mycobacterium tuberculosis*) and characterized by a thick wax-like coating on the surface of its cell which makes it highly impervious to water or water-soluble substances; and *Pseudomonas aeruginosa*, a Gram-negative, non-spore-forming bacillus which under some conditions is of pathogenic significance and produces a characteristic blue pus in contaminated wounds. The positive test demonstrated with respect to the last-named microorganism is particularly significant since there are few antagonistic substances or antibiotics capable of antagonistic action against such a microorganism.

The antagonistic water-soluble substances from the growth of *A. fumigatus* and *Monilia murmanica* in kerosine were found to be particularly effective against the above-described organisms.

In yields, the dried mycelia has been found to produce a consistent return of more than 21% of the crude extract containing the desired lipid materials in contrast to growth on dextrose under the same conditions when the yield ran only about 7.8% of the dry mycelia. On further refining with the removal of non-saponifiables, fat-like materials amounting to about 10% of the dry mycelia are obtained.

The use of surface-tension active agents has been found to increase the yields to some extent. In one case wherein *A. fumigatus* (Strain TDC No. 946) was used with kerosine, Span 80 (sorbitan monooleate obtainable from the Atlas Powder Co.) was added. A dilution of the surface-tension depressant was prepared in a degree of 1-80,000 and kerosine added thereto. The dilution was used in a proportion of 100 parts by volume with about 4.5 parts of kerosine. The resultant mixture was inoculated with 10 parts by volume of a thick suspension of the mold and incubated at 30° C. for about twelve days. The yield was increased about 30%. Other surface-active agents such as Roccal (Alkyl dimethyl benzyl ammonium chloride obtainable from Winthrop-Stearns, Inc.), sodium oleate, Tween 20 (sorbitan monolaurate polyoxyalkene derivative obtainable from Atlas Powder Co.) may also be used. The above represent typical surface-tension active agents of the cationic, anionic and non-ionic types.

Increases in yield have also been found where the inoculum is washed. Where 10% of an unwashed inoculum such as *A. fumigatus* (Strain TDC No. 946) was added to kerosine and a mineral salts medium, the yield was not as high as in a case wherein the mold was previously washed with mineral salts medium. Washing can be accomplished by thoroughly soaking the mold in freshly prepared mineral salt medium, draining off the excess liquid, and, by manual pressing, freeing the remaining liquid from the solid mold. Preferably, washing is repeated two or three times, the mold being finely suspended in the minerals salts solution. When washed inoculum was used, as compared with unwashed inoculum, an increase in yield of about 47% of the mold mycelia was obtained.

From the above it is believed apparent that the present invention provides a novel process for the synthesis of relatively valuable fat-like saponifiable materials, organic acids and antibiotics from relatively cheap raw materials, i. e. hydrocarbons.

Obviously many modifications and variations of the invention, as hereinbefore set forth, may be made without departing from the spirit and scope thereof and, therefore, only such limitations should be imposed as are indicated in the appended claims.

We claim:

1. A method of synthesizing fat-like, saponifiable materials and organic acids from hydrocarbons comprising the steps of dispersing hydrocarbon in the substantial absence of other organic substrate in an inorganic nutrient medium for microorganisms, inoculating the resulting mixture with a microorganism selected from the group consisting of *Penicillium* molds, *Aspergillus* molds, *Monilia* yeasts and *Saccharomyces* yeasts, subjecting the inoculated mixture to incubating conditions for a sustained period of time, collecting the resulting solid material and separating therefrom synthesized fat-like saponifiable materials and organic acids.

2. A method according to claim 1 in which the mixture is inoculated with *Penicillium notatum*.
3. A process according to claim 1 in which the mixture is inoculated with *Aspergillus fumigatus*.
4. A process according to claim 1 in which the mixture is inoculated with *Monilia murmanica*.
5. A process according to claim 1 in which the mixture is inoculated with *Aspergillus flavus*.
6. A process according to claim 1 in which the mixture is inoculated with *Pencillium glaucum*.
7. A process according to claim 1 in which the inoculated mixture is incubated at a pH of about 1 to 9 and at a temperature in the range of 20 to 45° C.
8. A process according to claim 1 in which the inoculated mixture is incubated in the presence of a surface tension depressant.
